[57] ABSTRACT

A lettering guide having a double clip member attached to the base thereof adapted to hold a tinted transparent window card and an image-producing card in fixed angular relationship with each other, so that lettering guide lines are reflected from the image-producing member onto a drawing surface to avoid the necessity of penciling in, and later erasing, lettering guide lines. The clip comprises a rigid inner member having two mutually opposing arms disposed at a predetermined acute angle with respect to each other, and a second outer clamping member having a pair of arms of flexible, resilient construction with a configuration paralleling that of the inner member. The two pair of arms form a cooperating pair of apertures in fixed angular relationship with each other for holding a transparent window card and an image-producing card.

5 Claims, 10 Drawing Figures

LETTERING GUIDE HAVING DOUBLE CLIP

This invention is an improvement over the device described in U.S. Pat. No. 3,291,552, issued Dec. 3, 1966.

A primary object of this invention is the provision of an improved double clip device which is sturdy and durable in construction, reliable and efficient in operation, and relatively simple and inexpensive to manufacture, assemble, utilize and maintain.

Another object of the instant invention is to provide a double clip device which, because of the designed flexibility and spring action of the outer clamping member of the device, will accommodate image producing cards and tinted windows of varying thickness thus avoiding problems of obtaining suitable fit when manufacturing tolerances on the thicknesses of the image producing cards and tinted windows are too great for these parts to fit properly in fixed slots.

A further object of the instant invention is the provision of one embodiment of a double clip device which is composed of two parts - an outer clamping part and an inner rigid part - bolted together.

Another object of this invention is the provision of one embodiment of a double clip device which is formed by cutting and bending one single part.

Other and further objects reside in the combination of elements, arrangement of parts and features of construction.

Still other objects will in part be obvious and in part be pointed out as the description of the invention proceeds and as shown in the accompanying drawings wherein:

FIG. 1 is a top plan view of one embodiment of the device of the instant invention as it would be attached to and a part of a lettering guide device associated with a conventional drawing machine, with parts broken away for illustrative clarity and convenience.

FIG. 2 is a side elevational view of the embodiment of FIG. 1 showing schematically the manner in which a draftsman or the like would utilize the device of the instant invention, with parts broken away for illustrative convenience.

FIG. 3 is a fragmentary sectional view taken on line 3-3 of FIG. 2 looking in the direction of the arrows, showing the device of the instant invention associated with the tinted window of the lettering guide device and showing the manner of adjusting the tinted window to facilitate use regardless of the position of the draftsman.

FIG. 4 is a top plan view of the device of the instant invention and the associated base 32 of the lettering guide device according to the embodiment of FIG. 1.

FIG. 5 is a side elevational view of the device of the instant invention and associated base of the lettering guide device shown in FIG. 4.

FIG. 6 is a transverse cross sectional view taken on line 6-6 of FIG. 4 looking in the direction of the arrows.

FIG. 7 is a top plan view of another embodiment of the double clip device of the instant invention associated with the base 32 of the lettering guide device.

FIG. 8 is a side elevational view of the embodiment of FIG. 7 with parts of the associated base 32 of the lettering guide device broken away.

FIG. 9 is a transverse cross-sectional view taken on line 9-9 of FIG. 8 looking in the direction of the arrows.

FIG. 10 is an end elevational view of the embodiment and associated base of FIG. 7.

Referring now to the drawings in general and more particularly to FIGS. 1 and 2, one embodiment of the double clip device of the instant invention is indicated generally by the reference numeral 11. It is shown as 10 part of a lettering guide device (indicated generally by reference numeral 10), which in turn is associated with a conventional drafting machine (indicated generally by reference numeral 12). The lettering guide device 10 and the drafting machine 12 are not parts of the instant invention except insofar as they cooperate with the double clip device 11. A knob 14 is provided on the drafting machine 12 and is used by the draftsman to move the machine in any direction as indicated by the arcuate arrows while maintaining a chuck means 16 in a constant position with relation to the drafting table 18 and drawing paper 20. Normally the chuck means 16 is maintained square with relationship to the edges (not shown) of the drawing paper 20 in order that a horizontally extending arm (not shown) secured to the chuck means 16 may be used for drawing horizontal lines while the vertically extending arm 22 is used for vertical lines.

A conventional locking means 24 is secured to the lettering guide device 10 to cooperate with the chuck means 16 in order to removably lock the lettering guide device 10 to the drafting machine 12 for operation in association therewith.

The preferred embodiment of the double clip device 35 11 as shown in FIGS. 1-6 comprises essentially an inner rigid member 13 and an outer clamping member 17.

The inner rigid member 13 and the outer clamping member 17 are fastened securely with conventional bolts 19 to the associated base 32 of the lettering guide 40 device 11. Fastened in position, the inner member 13 and the outer member 17 form a double clip which supports essential associated parts of the lettering guide device - a tinted window 28 and an image producing card 30. The inner rigid member 13 is stiff and inflexible and holds precisely the associated tinted window 28 and the associated image producing card 30 in predetermined fixed angular positions with respect to each other and the drawing surface 20 so that the letter guide device functions properly. The tinted window is held in an upward extending direction at a first angle with respect to said drawing surface and the image producing card is held in an upward extending direction at a second angle with respect to said tinted window, said first and second angles being substantially equal. The outer clamping member 17 is designed to have flexible, resilient action so as to accommodate cards and windows of different thicknesses and to hold each one securely against the inner rigid member 13. The inner rigid member 13 may be of any desired material so long as it can be formed into the correct angular configuration and be rigid enough to hold the correct configuration in use. Thin stainless steel sheet has been found useful. The outer clamping member 17 may be of the same material as the inner rigid member 13 or of different material so long as it provides the flexibility and resilience necessary. Stainless steel sheet also has been found useful for this member.

It will be noted that the space 21 between the inner rigid member 13 and the outer clamping member 17 is open on both ends. This enables the associated tinted window 28 to be angularly adjusted in the manner shown by the arcuate arrow in FIG. 3 to allow the draftsman to position the same to be most convenient and comfortable to him.

The use and operation of the double clip device 11 of the instant invention in conjunction with associated parts of the lettering guide device should now be apparent. The draftsman merely places the bottom portion of the tinted window 28 and the bottom portion of the image producing card 30 in their respective openings 21 in the double clip device and secures the associated base 32 of the lettering guide device to the chuck 15 means 16 of the drafting machine 12 by inserting the locking means 24 therein in the conventional manner. The tinted window member 28 may be angularly adjusted as shown in FIG. 3 and the draftsman, indicated schematically by the eye shown at 54 in FIG. 2, may 20 proceed to print whatever letters are desired, such as the "John Doe & Company" shown at 56 in FIG. 1 by means of the pencil 58 shown in FIG. 2. The guide lines 46 are reflected through the tinted window 28 from the image producing card 30.

The embodiment of FIGS. 7-10 is substantially the same so far as its utility is concerned as the embodiment of FIGS. 1-6. In this embodiment the double clip is formed in one piece. Outer clamping members 34 are partially cut and separated from the same piece that forms the inner rigid members 35. The outer clamping members 34 are shaped so as to provide flexibility and spring action. The number and size of the outer clamping members may vary as desired so long as the clamping action required is produced. The inner rigid members 35 are formed with flat surfaces positioned at the correct angles for the lettering guide device 10 to function properly.

It is now clear that there is herein provided a double clip device which satisfies all of the objectives of the in-

stant invention and others, including many advantages of great practical utility and commercial importance.

Since many embodiments may be made of this inventive concept and since many modifications may be made in the embodiments hereinbefore shown and described, it is to be understood that all matter herein is to be interpreted merely as illustrative and not in a limiting sense.

I claim:

- 10 1. A lettering guide having a double clip for holding a window card and an image-producing card, comprising in combination:
  - a base member;
  - a rigid inner clip member having a pair of arms disposed at a predetermined acute angle with respect to each other, said inner member being attached to the base member; and
  - 15 a flexible, resilient outer clip member having a pair of arms biased toward said arms of said inner clip member, so as to be disposed at said predetermined acute angle with respect to each other, said outer member being attached to the base so that the pair of arms of the outer member form a cooperating pair of slots with the corresponding arms of the inner member, said slots adapted to hold respectively a transparent window card and an image-producing card.
- 20 2. A lettering guide as set forth in claim 1, wherein the inner and outer members are bolted together to the base.
- 25 3. A lettering guide as set forth in claim 1, wherein the acute angle is approximately 60 degrees.
- 30 4. A lettering guide as set forth in claim 1, wherein the respective arms of the outer and inner members are of unitary construction.
- 35 5. A lettering guide as set forth in claim 5, wherein the respective arms of the outer member are partially cut and separated from the corresponding arms of the inner member.
